J. H. McILVAINE

VALVE MECHANISM FOR OIL BURNERS AND THE LIKE

Filed Aug. 23, 1926

Patented Nov. 20, 1928.

1,692,046

UNITED STATES PATENT OFFICE.

JOHN H. McILVAINE, OF LAKE FOREST, ILLINOIS.

VALVE MECHANISM FOR OIL BURNERS AND THE LIKE.

Application filed August 23, 1928. Serial No. 130,835.

This invention relates to valves generally and is more particularly concerned with a novel safety trip or shut-off valve especially designed for use with oil-burners but capable 5 of other applications.

The principal object is to provide an improved and simplified valve which is positive in its operation, is capable of simple adjustment to secure the desired degree of 10 sensitiveness, and is unaffected by ordinary changes in temperature or humidity or the particular conditions under which the valve may be made to operate, which oftentimes impaired or even prevented the proper operation of devices of this kind provided for 15 the purpose of shutting off the fuel supply for oil burners.

Another object is to provide a valve of the character described eliminating all springs 20 and embodying few parts constructed in a simple manner, capable of production at small cost, and not apt to get out of order or require any special attention after installation.

25 The invention is illustrated in the accompanying drawing wherein—

Figure 1 is a side view of my improved valve illustrated in connection with a centrifugal oil pump and air blower forming 30 part of an oil burning apparatus;

Fig. 2 is a plan view of the valve on an enlarged scale with the shield therefor appearing in section; and

35 Fig. 3 is a vertical sectional detail taken on the line 3—3 of Fig. 2 looking in the direction of the arrows.

The same reference numerals are applied to corresponding parts in the three views.

In illustrating the trip or shut-off valve of 40 my invention I have shown the same at 10 as mounted on a bracket 11 carried by a main supporting frame 12 which serves as an adjustable support for a centrifugal oil pump 13 and air blower fan 14. This arrangement is in accordance with the disclosure in my copending application Serial No. 679,467, filed December 8, 1923. As described in said application the frame 12 is 45 adjustable vertically on posts 15 to position the pump and blower at the desired elevation with respect to the fire-pot of the furnace. Oil is delivered to the pump 13 from a float chamber 16 through a pipe 17 and is arranged to be fed under a constant 50 pressure through the pipe 18 to the fire-pot. At the same time air is delivered in the 55 proper proportions through the conduit 19 extending from the blower 14. It will suffice for the present purposes to state that the oil is delivered to the float chamber 16 60 through a pipe 20 from a gravity tank or other source but that such fluid communication is arranged to be shut off in an emergency as may arise for example by the flame in the furnace being extinguished. For 65 this purpose the needle valve or other equivalent element in the float chamber 16 has the stem or some part affixed thereto projecting from the float chamber, as shown at 21, and arranged to be depressed to shut off communication between the pipe 20 and the float chamber 16 in an emergency such as that named. In the case of the flame of the 70 burner being extinguished, overflow fuel will be conducted through a pipe 22 from 75 the burner to a trip bucket or other suitable receptacle 23. There is also a possibility of excessive leakage or overflow into the drain pan 24 from the pump or its stand-pipe, or from the float chamber 16, all of which are 80 arranged over the pan 24. This leakage into the pan is conducted to the receptacle 23 through the pipe 25 to bring about the shutting off of the valve 10. In the case of the float chamber, there is little likelihood 85 of a lodging of any of the valve parts therein which would result in the failure of the valve during normal operation. In fact, the valve proper in the float chamber is floating normally and has no stuffing box or 90 bearing in which binding might occur but moves freely up and down as the fuel level changes in the regulation of the flame. However, if the valve should fail to close 95 properly when the level in the float chamber has risen to the proper point so that fuel would overflow into the drain pan 24, it is apparent that the loading of the bucket 23 would bring about the shutting off of the fuel feed in the same way as an overflow 100 from the firepot. The details of the novel trip mechanism for accomplishing the shutting off of the valve will now be described.

A valve operating lever 26 is pivoted at 105 27 in a yoke 28 mounted on top of the bracket 11. The bucket 23, previously referred to, is suspended from the one end of the lever 26, as shown at 29, and a counter-weight 30 is provided on the other end of said lever which approximately counter- 110 balances the bucket except when the latter is loaded with oil. The lever 26 extends di-

rectly over the valve stem 21 and is arranged to depress the same when the lever is tilted by the loading of the bucket 23. An auxiliary means is provided to insure the complete closing of the valve by the lever 26. This comprises a hammer element or other weighted member 31 arranged to drop onto the lever 26 at the proper time and by reason of the blow to insure definitely that the valve closing movement will be completed. The weighted member 31 has a forked portion 32 straddling the lever 26 and pivoted therewith at 27. The outer or head portion 33 is forked as indicated at 34 to drop astride the lever 26, as indicated in dotted lines in Fig. 1, and thus make the full weight of the element effective in the closing of the valve. A lateral extension or arm 35 is provided on the forked portion 32 of the hammer element in which an adjustable set screw 36 is threaded and arranged to engage the lever 26. The adjustment of the set screw 36 determines the sensitivity of the trip mechanism as a whole and the same may be fixed in its adjusted condition by a lock nut 37.

In operation the hammer element 31 is normally raised to its cocked position, as shown in full lines in Fig. 1. In this dead center position practically all of the weight of the element is borne by the pivot 27. The lever 26 is therefore unencumbered and is perfectly free to tilt under the loading of the bucket 23 by leakage, overflow, or excess feed of fuel. According to the adjustment of the screw 36 the hammer element 31 will be tripped and fall to the dotted line position after a certain amount of oil has entered the bucket. The dropping of the hammer element is usually so timed as to occur when the lever 26 has engaged or has partly closed the valve by depression of the stem 21. The blow of the hammer element merely serves to complete the closing of the valve and is a definite insurance against hazardous operation. It will be obvious that the resetting of the trip mechanism is a very simple matter. The mere act of raising the hammer element 31 to the cocked position moves the lever 26 back to its normal position. Communication is thus re-established between the pipe 20 and the float chamber 16.

It will be apparent that the valve of my invention eliminates all springs and embodies very few parts which are all of simplified construction and will require no attention after installation. What moving parts are employed occur in such form as to be practically unaffected by any ordinary operating conditions to which the valve may be subjected in service. For the purpose of preventing the possibility of laying tools, rags, waste, etc., on the trip mechanism and incidentally to protect the same from fall-

ing débris, soot, dust, and dirt, I prefer to provide a shield 38 which has a top span 39 affording protection from above, a side span 40 affording protection from the side, and a front span 41 affording protection on the furnace side. The shield 38 is suitably secured to the yoke 28 by the pivot bolt 27, as shown in Fig. 3, and has a part bearing against the bracket 11 for support, as shown at 42. Obviously the open side of the shield affords easy access to the hammer element 31 for setting the valve and to the set screw 36 for adjusting the same.

It is believed that the foregoing conveys a clear understanding of the invention and of its purposes and advantages and while but a single working embodiment has been illustrated it should be understood that certain changes might be made in details of construction as well as arrangement without departing from the spirit and scope of the invention as expressed in the appended claims.

I claim:

1. A shut-off valve of the character described comprising a lever pivoted intermediate its ends, said lever having a counter-weight on one side of its pivot, a normally empty receptacle supported by said lever on the other side of its pivot and arranged to be loaded in a certain eventuality, said receptacle when empty being approximately counterbalanced by said weight, a valve member to be operated when said receptacle is loaded, and a weighted member for operating the same, said weighted member being pivoted and arranged to be raised to a dead center cocked position, and having a part moved by said lever as the same is tilted by the load of said receptacle whereby to cause said weighted member to drop and thereby operate said valve member, the parts being so arranged that the movement of the weight member to cocked position brings the lever with its counter-weight to normal position.

2. In a device of the character described, the combination with a casing having a valve operating stem projecting therefrom and arranged to be depressed to close fluid communication with said casing, of an operating lever pivotally supported intermediate its ends and projecting over said stem to depress the latter, a normally empty receptacle supported on said lever and arranged to be loaded in a certain eventuality, a counter-weight provided on said lever on the opposite side of its pivot from said receptacle arranged to balance the weight of the latter except when the same is loaded, and a weighted member pivotally mounted adjacent said lever arranged to be set in a raised cocked position and to be tripped by said lever as the latter is tilted in the loading of said receptacle, said weighted member being thereby caused to drop onto said lever

- over the valve operating stem to insure the depression of the latter.
3. A device as set forth in claim 2, including an arm on said weighted member having a portion thereof extending over said lever, and an adjustable set screw extending through said arm and engaging said lever.
4. In a shut-off valve of the character described, the combination of a valve operating lever pivoted intermediate its ends on a support, a fluid receptacle suspended from one end of said lever, a weight provided on the other end of said lever counterbalancing the weight of said receptacle except when the latter is loaded, and a hammer element for delivering a blow onto said valve operating lever on the receptacle side of the pivot thereof to insure a valve closing movement of said lever when said receptacle becomes loaded to a certain degree, said hammer element comprising a forked portion straddling said lever and having a lateral extension projecting over said lever for operation thereby.
5. A shut-off valve as set forth in claim 4, including an adjustable set screw on said lateral extension for engaging said lever to determine the cocked position of said hammer element.
6. A shut-off valve as set forth in claim 4, wherein the hammer element has a forked head portion to fall astride said valve operating lever.
7. In a device of the character described, the combination with a casing having a valve operating part projecting therefrom, of an operating lever pivotally supported adjacent said casing, a receptacle supported by said lever on one side of its pivot and arranged to receive fluid to cause the operation of said operating lever and valve operating part, a counterweight on said lever on the other side of its pivot approximately counterbalancing the weight of said receptacle when empty, a pivoted hammer element arranged to be set manually in a raised cocked position and to drop to deliver a blow onto said operating lever to insure a complete valve operating movement thereof, said hammer element having a part arranged to be operated by said lever whereby to be tripped from its cocked position, and a shield enclosing said operating lever and said hammer element except on one side at which access is afforded to said hammer element for raising the same to its cocked position, said hammer element and said operating lever being so arranged that the operation of the former to its cocked position also operates the latter to its normally inoperative position.
8. In a shut-off valve mechanism, the combination with a casing having a valve operating stem projecting therefrom and arranged to be depressed, of an operating lever pivotally mounted so as to project over said stem to depress the latter, a trip bucket supported on said lever, said lever tending to occupy a normal position balancing the empty bucket, and a drop weight pivotally mounted adjacent said lever arranged to be set in a raised cocked position and to be tripped by said lever when the latter is tilted due to the loading of said bucket, said weight being thereby caused to drop onto said lever over the valve operating stem to insure the depression of the latter.
9. A device as set forth in claim 8 including a shield enclosing said lever and drop weight but permitting access to the latter so that the same may be raised to cocked position.
10. In a shut-off valve mechanism the combination with a casing having a valve operating stem projecting therefrom and arranged to be depressed, of an operating lever pivotally mounted so as to project over said stem to depress the latter, a trip bucket supported on said lever, and a drop weight pivotally mounted adjacent said lever and arranged to be set in a raised cocked position where it tends to keep the lever in a normal position balancing the empty bucket, said weight being arranged to be tripped by said lever when the latter is tilted due to the loading of said bucket and being thereby caused to drop onto said lever over the valve operating stem to insure positive depression of the latter.
11. A device as set forth in claim 10 including an arm on said drop weight having a portion thereof extending over said lever, and an adjustable set screw extending through said arm and engaging said lever whereby the cocked position of said weight is adjustable.
12. A device as set forth in claim 10 wherein the drop weight has a forked head end arranged to fall astride said valve operating lever.
13. In a valve mechanism, the combination with a valve to be operated, of an operating lever swingable to operate the valve, a trip bucket supported on said lever, said lever tending to occupy a normal position balancing the empty bucket, a drop weight pivotally mounted adjacent the lever arranged to be set in a raised cocked position and to be tripped by said lever when the latter is tilted due to the loading of said bucket, and a shield for protecting at least some of the parts mentioned against accidental operation of the mechanism but permitting access thereto to permit raising of the drop weight to cocked position.
- In witness of the foregoing I affix my signature.
- JOHN H. McILVAINE.
